K. DOUGAN,
APPAREL BELT BUCKLE,
APPLICATION FILED APR. 14, 1921.

1,398,632.

Patented Nov. 29, 1921.

INVENTOR
Kennedy Dougan

UNITED STATES PATENT OFFICE.

KENNEDY DOUGAN, OF MINNEAPOLIS, MINNESOTA.

APPAREL-BELT BUCKLE.

1,398,632.

Specification of Letters Patent. Patented Nov. 29, 1921.

Application filed April 14, 1921. Serial No. 461,261.

To all whom it may concern:

Be it known that I, KENNEDY DOUGAN, a citizen of the United States, residing at Minneapolis, in the county of Hennepin and State of Minnesota, have invented certain new and useful Improvements in Apparel-Belt Buckles, of which the following is a specification.

My invention relates to improvements in apparel belt buckles of the species in which the free end of the belt is hidden beneath the fixed end, and the objects of my improvements are to provide a belt that will not abrade the apparel of the wearer, be durable and slightly and conceal the adjustable end of the belt when being worn.

I attain these objects by the means illustrated in the accompanying drawings, in which,—

20 Figure 1 is a central horizontal section through the buckle showing both the fixed and free ends of the belt in full lines and means for securing the buckle to the belt.

25 Fig. 2 shows the body side of the buckle with both ends of the belt secured to the buckle.

Fig. 3 is a plan view of the buckle with both the fixed and free end of the belt shown partly in dotted lines.

30 Fig. 4 shows an end view of the buckle without the belt, looking toward the right in Figs. 1 and 2.

Fig. 5 is a transverse section through the buckle at its center looking toward the right.

Fig. 6 is an end view of the buckle looking toward the left. Figs. 7 and 8 show a modified form of the device for holding the fixed end of the belt.

40 Fig. 9 shows the buckle curved to fit the body of the wearer, and shows also a modified form of a portion to be explained here-in later.

Figs. 10 to 13 inclusive show slight modifications of parts to be explained later.

Referring to Figs. 1 to 6 inclusive:

1 is the fixed end of the belt; 2, the adjustable end of the belt which is held between the flat surface 3 of the buckle and the belt holder 4 which is slidable between surface 3 and the inwardly turned sloping portions 5 of the sides 6. It will be noticed that the sides 5 are narrower at the middle than at the ends and that the edges serve to retain belt holding devices 4 and 11 in contact with the belt. The outer ends of parts

5 are too close to surface 3 to allow parts 4 and 11 to drop out when the belt is not in use. In placing parts 4 and 11 the sides 5 are sprung apart slightly near the middle 60 of the buckle and the parts forced into place, the sides springing back prevent their coming out.

When inserting the free end of the belt in the buckle, belt holder 4 is drawn toward 65 the center of the buckle and the thumb pressed upon portion 7 which draws the holding end 8 away from surface 3, the portion 9 acting as a fulcrum. After the end of the belt is pushed under end 8 the thumb is 70 removed from end 7 allowing it to raise when the end of the belt is advanced. In securing the free end of the belt to the buckle, belt holder 4 is pushed to the right with the left hand while the belt is simultaneously pulled with the right.

10 is an opening formed in belt holder 4, over which the thumb may be placed when moving said belt holder; the object of said hole is to insure greater friction between 80 thumb and belt holder.

The means for holding the fixed end of the belt are identical with those described for holding the free end except that portion 7 is omitted from belt holder 11 and the 85 belt holding portion has teeth 12 in it as shown in Fig. 4. In order that there shall be no obstruction for the free end of the belt to strike when being pushed through the buckle the inner portion of belt holder 90 11 is beveled as shown in Fig. 1 and formed arcuate as shown in Fig. 7, the object being to have the inner edge always in contact with surface 3 should surface 3 curve from the belt pressure as shown in Fig. 11. 95 Should it be found that the free end of the belt in passing over the belt holder 11 would incline to stick between said holder 11 and the edge of portion 5 of the buckle, said holder 11 may be made as shown in Figs. 100 7 and 8, 7 being a view from the body side and 8 a view in the direction of the arrow. The portion 14 is beveled as shown in Fig. 7 and the end of the belt striking the beveled portion is guided toward the center of the 105 buckle.

Fig. 9 shows a top view of what will probably be the preferred form of the buckle. The upper side 6 is partly broken away to show the lower portion 5, the idea being to 110 decrease the pitch or angle of the edge of portion 5 so that increased pressure will

be put on the belt holders as they near the end of the buckle.

Referring to Fig. 10 which shows the sides 5 folded down close upon sides 6: The object of having sides 5 spaced away from sides 6 as shown in some of the figures, is merely to furnish a widened portion for contact with the clothing so as to reduce injurious wear thereon, but practice may demonstrate that spacing away of said sides is not necessary. 15 are projections of the form shown, their function being to offer an additional safeguard against the dropping out of parts 4 and 11.

Referring to Figs. 11 and 12,—it will be noted that the working edges of sides 5 are beveled and that there are beveled notches formed in the ends of belt holder 4, the object of which is to prevent the possibility of belt holder 4 slipping out when in use, and great pressure is exerted thereon and when the buckle is made of very light material. 16 are projections turned in on side pieces 6 to prevent the possibility of losing parts 4 and 11 when the belt is not in use. Should the pressure of holder 11 tend to curve the buckle as shown in Fig. 11, the teeth may be made shorter in the middle of the holder as shown in Fig. 13 which is a diagrammatic view with a portion shown broken away.

The operation has been explained as the description proceeded.

I claim:

1. A belt buckle including a front plate having parallel sides, tapering grooves formed in said sides adjacent said front plate the sides of said grooves converging

toward the ends of said buckle, and belt holding means in said grooves adapted to hold the belt by forcing it against said front plate.

2. A belt buckle including a front plate having parallel sides, tapering grooves formed in said sides adjacent said front plate the sides of said grooves converging toward the ends of said buckle, belt holding means in said grooves adapted to hold the belt by forcing it against said front plate, and loose part retaining means.

3. A belt buckle including a front plate having parallel sides, tapering grooves formed in said sides adjacent said front plate the sides of said grooves converging toward the ends of said buckle, belt holding means in said grooves adapted to hold the belt by forcing it against said front plate, and means for guiding the belt into the middle of the buckle.

4. A belt buckle including a front plate having parallel sides, tapering grooves formed in said sides adjacent said front plate the sides of said grooves converging toward the ends of said buckle, belt holding means in said grooves adapted to hold the belt by forcing it against said front plate, and means for preventing spreading of the sides of said buckle when unusual strain is put upon the belt.

April 11th, 1921.

KENNEDY DOUGAN.

Witnesses:

FRED GARDNER,
S. SHUFELDT.
